HOLDING MEANS FOR LOOM BUSHINGS

Woodrow W. Usry, Langley, S. C.

Application June 20, 1951, Serial No. 232,504

2 Claims. (Cl. 139—158)

1

My invention relates to improvements in picker mechanism for looms; and more particular to the holding means for the bushing which receives the guide rod or spindle for the picker.

In at least one type of automatic loom for the weaving of textile fabrics, the picker is slideable on a guiding rod or spindle one end of which is supported in a bushing which is screwed into a threaded opening in the lay end-plate of the loom. In the operation of the loom the vibration and the shock incident to boxing of the shuttle, causes the externally screw threaded bushing for the picker rod to work loose and thereby interfere with the proper guiding of the picker and the shuttle. The vibration is such that the screw threads in the hole of the lay end-plate wear to such an extent that the plate must be replaced by a new one as often as twice a year. That, of course, means not only the substantial cost of the new lay end-plates and the cost of replacement labor, but also the loss due to the loom being out of service. Various attempts have been made to overcome this trouble but they have not been entirely satisfactory, and the loom manufacturer has continued to use these troublesome threaded bushings without any locking or holding means therefor. After considerable study and experimental work with different means for holding the threaded bushing, I have thoroughly tested the one herein disclosed and have found it to be entirely effective and satisfactory. The principal object of the invention is, therefore, to provide an improved holder or lock for the screw threaded bushing which holds one end of the picker guiding rod or spindle of a loom.

Such threaded bushings are provided with hexagonal wrench-engaging heads to permit them to be screwed into the threaded holes in the lay end-plates, and it is another object of the invention to provide a holding or locking device which may be applied to the bushing head in any of the various positions it may be in when it is tightened in its threaded hole in the lay end-plate.

Another object is to provide a device of this character which is simple, effective and relatively inexpensive, and which may be quickly and easily applied.

With the above and other objects and advantages in view, the invention resides in the novel combinations and arrangements of parts and the novel features of construction hereinafter described and claimed, and illustrated in the accompanying drawings which show the present preferred embodiment of the invention.

2

In the drawings:

Figs. 1 and 2 are perspective views of the opposite sides of parts of a well known type of loom to illustrate the application of the invention;

Fig. 3 is an elevation of the outer face or side of a lay end-plate showing my locking or holding device applied thereto and to the head of the bushing, the picker guide rod being also shown and a part of the end-plate being broken away;

Fig. 4 is a vertical sectional view on line 4—4 of Fig. 3, and

Fig. 5 is a perspective view of the new bushing holding or locking member.

In Figs. 1 and 2 are shown parts of the well known C-6 automatic textile fabric weaving loom marketed by Crompton & Knowles Loom Works of Worcester, Massachusetts, Fig. 1 showing my bushing holding member applied to the lay end-plate 10. This plate 10 is removably fixed to the end of the frame work 11 of the lay and is formed with a screw threaded hole 12 which receives the bushing 13.

The plate 10 is also formed with vertically extending slots 14, one above and the other below the hole 12 as seen in Fig. 3. The bushing 13 is in the form of a cylindrical sleeve with an enlarged hexagonal or other flat faced head 15 at one end to which a wrench may be applied. The exterior of the sleeve or body is screw threaded from its head to its opposite end for engagement with the threads in the hole 12. The cylindrical bore 16 through the bushing is of a diameter to snugly receive and support one end of the guide rod or spindle 17 for the slideable picker, the rod 17 also passing through a hole in a part of the lay frame 11, as seen in Fig. 4. The other end portion of the rod or spindle 17 which carries the usual buffer 18 for the picker stick is suitably supported and held against rotary and endwise movement on the lay frame. The above described parts are all old in the above identified loom.

My invention comprises a bushing engaging and holding member or plate 25 and means for adjustably fastening it to the lay end-plate 10. The member 25 may be cast or otherwise formed of suitable metal, and it is preferably in the form of a substantially flat elongated plate, one end portion 26 of which may be of substantially circular outline while the other end portion 27 may be of generally segmental shape. Formed centrally in the smaller end 26 is a flat walled hole or opening 28 shaped to snugly receive the head 15 of the bushing, such head being usually of hexagonal shape. The larger end 27 is formed with an arcuate slot 29 which is concentric with

the center of the hole 28 and hence with the bore 16 of the bushing 13 when the end 26 is seated on the head 15 as shown in Figs. 3 and 4. The size and proportions of the locking member or plate 25 are such that when it is applied to the bushing the slot 29 may be disposed across either of the slots 14 in the lay end-plate, and hence a clamping bolt 30 disposed in the intersecting slots may be used to securely fasten the device to the lay end-plate. The head of the bolt may engage the outer face of the portion 27 and on the screw threaded end of the bolt there are applied an ordinary washer 31, a lock washer 32 and a nut 33, as seen in Fig. 4. The provision of the slot 29 in connection with the hexagonal hole 28 is important since it permits a portion of the slot 29 to intersect one or the other of the slots 14 without regard to the position of the head 15 when the bushing is screwed tight in the hole 12.

When the bolt 30 is tightened to rigidly clamp the device against the lay end-plate the bushing 13 will be rigidly held even though the threads in the hole 12 have been worn because hole 28 is of a size to snugly fit the head 15. An extended test of the device has shown that it will effectively prevent the loosening of the bushing and wear of the threads in the hole 12 so that the life of the lay end-plate is greatly extended. The use of the device therefore saves considerable expense in the operation of a loom.

In the drawing the spindle or rod 17 is shown as terminating at the outer face of the bushing head 15 but in practice it projects beyond said outer face. In some looms such projecting end carries a small oil or grease box to lubricate the spindle. Also in some looms a metal strip bears against such projecting end of the spindle to prevent end-wise movement of the latter. These old parts are not illustrated, but their use does not interfere with the application of my invention since the plate 25 lies in the plane of the head 15. The slots 14 in the lay end-plate receive bolts for fastening the latter to the lay frame 11. One of these bolts may be the bolt 30 which is in such case made a little longer than the bolt (not shown) in the other slot 14.

From the foregoing, taken in connection with the accompanying drawing, it will be seen that novel and advantageous provision has been made

for carrying out the objects of the invention, and while preferences have been disclosed, attention is invited to the possibility of making variations within the scope of the invention as claimed.

I claim:

1. Means for holding in a slotted lay end-plate a screw threaded bushing which supports one end of a guiding spindle for a picker, the bushing having a flat faced wrench-engaging head, said means comprising a substantially flat and elongated plate having at one end a flat-walled opening shaped to fit the head of the bushing and at its other end an arcuate slot concentric with said opening and disposable in intersecting relation with the slot in the lay end-plate, and a screw threaded fastening to be positioned in the intersecting slots for clamping said plate against the lay end-plate.

2. The combination of a lay end-plate having a screw threaded hole and a slot adjacent said hole, a bushing to hold one end of a picker guiding spindle, said bushing having a flat-faced head at one end, its other end having external screw threads to engage the threads in said hole, a bushing-holding plate having a flat-walled opening to fit said head of the bushing and an arcuate slot concentric with said flat-walled opening and disposed in intersecting relation to said slot in the lay end-plate, and a screw threaded fastening in said intersecting slots to clamp said holding plate against said lay end-plate.

WOODROW W. USRY.
